UNITED STATES PATENT OFFICE.

RODNEY C. IRWIN, OF KANSAS CITY, MISSOURI, ASSIGNOR TO A. H. HEISEY & COMPANY, OF NEWARK, OHIO, A PARTNERSHIP.

DESIGN FOR A COMBINATION CIGARETTE HOLDER AND ASH TRAY.

Application filed November 19, 1928. Serial No. 28,941. Term of patent 14 years.

To all whom it may concern:

Be it known that I, RODNEY C. IRWIN, a citizen of the United States, residing at Kansas City, in the county of Jackson and State of Missouri, have invented a new, original, and ornamental Design for a Combination Cigarette Holder and Ash Tray, of which the following is the specification, reference being had to the accompanying drawings, forming a part hereof.

Fig. 2 is a longitudinal sectional view through Fig. 1.

I claim:

The ornamental design for a combination cigarette holder and ash tray, as shown.

RODNEY C. IRWIN.
